UNITED STATES PATENT OFFICE.

BARTHOLOMEW J. CONLON, OF LAWRENCE, MASSACHUSETTS, ASSIGNOR, BY MESNE ASSIGNMENTS, TO PAGE MACHINE COMPANY, INC., OF HAVERHILL, MASSACHUSETTS, A CORPORATION OF MASSACHUSETTS.

HEEL-ASSEMBLING MACHINE.

1,188,414.

Specification of Letters Patent. Patented June 27, 1916.

Application filed September 24, 1913. Serial No. 791,492.

To all whom it may concern:

Be it known that I, BARTHOLOMEW J. CONLON, a citizen of the United States, residing at Lawrence, in the county of Essex and State of Massachusetts, have invented an Improvement in Heel-Assembling Machines, of which the following is a specification.

This invention relates to certain improvements in heel-assembling machines of the type shown in the pending application of E. L. Page #695,018, in which an endless carrier is provided which comprises a series of connected heel-holders on which the heels are successively built as the carrier is moved automatically from one position to the next, in connection with heel-clamping means which act to press the cemented lifts together after they have been piled on the holder, so that the heel will be held under pressure until the cement becomes set, the heel being automatically discharged from its holder as the latter approaches the position in which it was previously filled;—this operation being carried on continuously. With said prior device it is necessary to provide a heel-forming device on each holder, in which the heel is built, and as it is, in practice, frequently necessary, to build heels of different styles, it is necessary with this machine, to provide a set of heel forms for each style of heel which is to be built upon the machine. This not only causes a large initial expense for the holders, but it also requires considerable time to change all the forming devices on the holders each time it is desired to make a heel of different shape.

The object of my invention is to provide the machine, above referred to, with a heel-forming device, which is adapted and arranged to be held in position on each holder, while the heel is being assembled thereon, until the heel has been clamped thereon, so that the lifts will not thereafter become misplaced, and which may then be moved out of engagement with the heel into assembling position over the next succeeding holder, so that the same heel-forming device will be used in shaping all heels which are formed, and so that when it is necessary to change the style or shape of heels which are to be built, it is only necessary to change one set of heel engaging parts, thereby saving expense and greatly increasing the production

of the machine. I accomplish this object by the means shown in the accompanying drawing, in which,

Figure 1 is a side elevation of a heel-assembling machine provided with my invention. Figs. 2 and 3 are detail plan views thereof showing the parts in different positions. Fig. 4 is a similar view in front elevation. Fig. 5 is a cross section on line 5—5 of Fig. 4. Fig. 6 is a detail view of the connecting mechanism. Fig. 7 is a detail view of the releasing mechanism.

In the drawings only a sufficient portion of the machine is shown to illustrate my invention and its application to the particular prior machine above referred to.

The machine comprises two vertically disposed side frames 1 and 2, in the inner sides of which endless grooves 1' and 2' are provided, said grooves extending horizontally for a greater portion of the length of said frames and being semicircularly curved at the ends thereof. An endless carrier is provided, which comprises a series of holders in the form of rectangular plates 3, said plates being connected together by short links 4, having projecting lugs 4' thereon which are arranged to travel in the grooves 1', 2'. Suitable driving means is provided, which preferably comprises a shaft 5, arranged at the center of the curve of the grooves at one end of the side frames, and an arm 6, which is mounted to swing thereon, said arm having a pawl 7 at its end which is adapted to engage lugs or teeth 8 on the inner side of the plates 3, said arm 6 being swung by any suitable power driven means, which may include a connecting rod 9. The arrangement is such that the pawl 7 will be held in position to engage one of the lugs 8 when the arm 6 is in an approximately vertical position, so that, when the arm 6 is swung forwardly said carrier will be moved along in the grooves, the distance which it is moved being arranged to correspond to the distance from the center of one plate to the center of the next.

Each holder plate 3 is provided with a vertically disposed breast-gage 10, which is arranged in the rear of the middle portion thereof which is adapted to receive the heels which are to be built thereon, said gage being of sufficient height to correspond to the

height of any heel which is to be built on the machine. Clamping means for each holder plate 3 is provided, said means preferably comprising a presser plate 11, which 5 is carried on the end of a stem 12, said stem being adjustably mounted in the end of an arm 13 at right angles thereto. Each arm 13 is mounted on a rod 14, and is arranged to swing in planes parallel to the surface of the 10 particular holder plate 3 in which it is mounted, each rod 14 being mounted perpendicularly in its corresponding plate 3, in the rear of its breast-gage 10, and being adapted to slide therein to raise and lower the plate 15. A spring 15 is mounted on the lower end of each rod 14, between the under side of the plate 3, and a head 14' on the lower or inner end of the rod, so as to draw said plate 11 inwardly. A rib 2^a is 20 formed on the inner side of the rear frame 2 in position to engage said head 14', so that, when a holder plate 3 reaches a certain position, said head 14' will be carried into engagement with said rib 2^a, which 25 will force said rod 14 outward, so that the plate 11 may be moved out of clamping position, and swung aside to permit the heel which was clamped to fall from the holder, and another heel to be assembled 30 therein.

A carriage 16 is slidably mounted on a pair of horizontal guide-rods 17 secured on the front side of the frame 1, and two supports 18 and 19, are connected to the upper 35 end thereof and extend horizontally over the carrier, or series of connected holder plates 3, the support 18 being rigidly connected to the carriage 16, and the support 19 being pivotally connected thereto by means 40 of a pivot bolt 20, which is arranged in front of the carriage 16. A spring 30 connects said supports 18 and 19 and normally holds the latter in the position of Fig. 3.

A pair of fingers 21 are respectively 45 mounted to slide on the supports 18 and 19, in grooves 18^a, 19^a. When the support 19 is in its normal position, shown in Fig. 3, said grooves extend convergently toward the breast-gage 10, said fingers 21 being 50 held in position by bolts 23 which pass through slots therein and springs 24 being interposed between the front ends of said slots and said bolts 23, so that said springs tend normally to push said fingers forwardly, and hold the rear ends of said slots against said bolts. Heel-formers 25 are 55 detachably connected to the ends of said fingers 21, the heel engaging faces thereof being arranged to correspond to the curved rear portions of the heel at each side of the middle line thereof, the arrangement being such that when a heel is supported on a plate 3 with its breast portion arranged in engagement with the breast-gage 10, the heel-formers 25 will bear against the curved

rear side portions of the heel at equal distances from, and at opposite sides of its middle line. With this arrangement, when the lifts are placed in the space between said formers and the breast-gage, they will 70 be pushed into the desired position, the springs 24 merely yielding when necessary to permit the lifts to become properly arranged, or to accommodate over-sized lifts.

A bell-crank lever 31, having vertically 75 and horizontally disposed arms, is mounted on a pivot 32 in the carriage 16, and the horizontal arm has an upwardly extending lug 31', at its end which is adapted to engage the outer edge of the support 19, and 80 lock the same in the position of Fig. 1. A bell-crank lever 33 is mounted on a pivot 34 in the carriage 16, at the left-hand end thereof, and has a depending lug 33' at one end, which is adapted by its gravity, to 85 enter any one of the apertures 35 with which each holder plate 3 is provided. An unlocking bar 36 is slidably mounted on the front side of the carriage 16, and is provided with a laterally projecting arm 37 90 and an inclined end face 36'. A lug 38 is formed on the opposite end of lever 33 from its end bearing lug 33', which is arranged to be engaged by said face 36', and the arm 37 is provided with an inwardly projecting 95 lug 37' arranged to engage the depending arm of lever 31.

A spring 39 is attached to the carriage 16 and normally holds the same in position opposite the middle of the position in which 100 each holder plate is held when the heel lifts are placed therein, which I will hereafter term the initial position, and a spring 40 is attached to the depending arm of lever 31 and normally holds the same in the position 105 of Fig. 4.

The operation of the device is as follows:—The parts being in the position of Figs. 1, 3, 4 and 5, the heel is built by placing the cemented lifts therein, in the usual 110 manner. When the heel has been assembled in the form, the driving mechanism is operated and, as the carrier is moved, a projection 41 on frame 2, strikes on a lug 42 on arm 13, and throws the presser-plate 11 into clamping position over the heel. The head 14' of bolt 14 then moves out of engagement with rib 2^a, so that the clamping-plate 11 is moved into clamping engagement with the heel. The carriage 16 is then 115 locked to a holder plate 3 by means of the lever 33, which enters its apertures 35, and as the carrier moves forward, it draws the carriage 16 with it until the end of the bar 36 engages a stop-bracket 43 mounted on rods 17, and causes the bar to be pushed back longitudinally with relation to the carriage. This action causes the inclined face 36' to engage the lug 38 of the lever 33 and press the same down, lifting the lug 125 130

33' out of the aperture 35, and unlocking the carriage from the plate 3, which the lever 33 was engaging. While this is occurring, the lug 37 engages the bell-crank lever 31 and draws its lug 31' downwardly out of engagement with the support 19, unlocking the same, the parts being relatively timed, so that the support 19 is unlocked from the carriage 16 just before the carriage 16 is unlocked from the holder plate 3. The result is, that, as soon as the carriage 16 is unlocked, the spring 39 will draw back said carriage to the initial position, the support 19 being then free to swing away from the heel, so that the former 25, which it carries, will pass the heel, as shown in Fig. 2. By this time the carrier will have reached the next initial position, and, as the carriage moves opposite the next plate, the lug 31' will fall into its aperture 35, locking the carriage thereto, and, as soon as the former 25 clears the heel, as above described, the spring 30 will return the support 19 to its normal position, and the spring 40 will then return the lever 31 to its normal position, to lock the support 19. The above described operation may then be repeated.

With the above described device, when it is desired to build a heel of different form from that for which the formers 25 are adapted, it is merely necessary to remove said formers and replace them with others of the desired shape, the breast-gage 10 being adapted for all shapes. The expense of adapting the machine to differently shaped heels is therefore very small and but little time is required to make the change.

It will be observed that a prime essential to the above described mechanism is the holding of the forming devices in forming position until the heel is pressed firmly on the holder plate, so that the lifts will not become displaced, after which the forming devices may be disengaged from the heel, so that the holder may be moved on, and the forming devices be returned to their initial positions. The particular manner in which this result is accomplished is of secondary importance.

I claim:

1. In a heel-assembling machine, a series of heel holders successively movable from an initial position, a lift-clamping means for each holder, a heel forming device arranged to be held in coöperative relation with each holder when in said position to permit a heel to be formed thereon, means to move said clamping means into clamping engagement with the heel while held by said forming device, and means permitting movement of said forming device out of engagement with the heel while held by said clamping means.
2. In a heel-assembling machine, a series

of heel holders successively movable from an initial position, a lift-clamping means for each holder, a heel forming device arranged to be held in coöperative relation with each holder when in said position to permit a heel to be formed thereon, and means successively to move said clamping means into clamping position and said forming device out of forming position with relation to one holder and into forming position with relation to the next holder. 75

3. In a heel-assembling machine, a series of heel-holders successively movable from an initial position, a lift-clamping means for each holder, a heel-forming device, and means successively to hold the same in forming relation with each holder, substantially as described. 80

4. In a heel-assembling machine, a series of heel-holders successively movable from an initial position, lift-clamping means for each holder, a heel-forming device, and means successively to operate said clamping means to clamp a heel held by said forming device and to move said forming device into forming relation with the next holder. 85

5. In a heel-assembling machine, a series of connected heel holders successively movable from an initial position, a heel-forming device, arranged to be held in heel-forming relation with one holder when in said initial position, means to clamp the heel on said holder while held by said forming device, and means thereafter to move said forming device into forming relation with the next holder. 95

6. In a heel-assembling machine, a series of connected heel holders successively movable from an initial position, a heel-forming device, arranged to be held in heel-forming relation with each holder successively, and clamping means for each holder arranged to clamp a heel supported thereby while held by said forming device. 105

7. A heel-assembling machine comprising an endless carrier composed of a series of heel holders and means to move the same in one direction to carry said holders successively from an initial position, clamping means for each holder, and a heel shaping device arranged to be normally held in forming relation with each holder when in said position and movable out of forming relation therewith as the holder is moved to a succeeding position. 110

8. In a heel-assembling machine, a series of heel holders successively movable from an initial position, a lift-clamping means for each holder movable into clamping position when the holder is moved from initial position, a heel-forming device and means to hold the same in coöperative relation with each holder when in said initial position, to form the heel thereon, means permitting movement of said forming device with each 125

- holder as the holder moves from said initial to clamping position, and means to return said forming device to said initial position.
9. In a heel-assembling machine, a series 5 of heel holders successively movable from an initial position, a lift-clamping means for each holder movable into clamping position when the holder is moved from initial position, a heel-forming device and means 10 to hold the same in coöperative relation with each holder when in said initial position, to form the heel thereon, means to move said forming device with the holder from said initial to said clamping position, and means 15 for automatically returning said forming device to said initial position.
10. In a heel-assembling machine, a series 20 of heel holders successively movable from an initial position, a lift-clamping means for each holder movable into clamping position when the holder is moved from initial position, a heel-forming device and means 25 to hold the same in coöperative relation with each holder when in said initial position, to form the heel thereon, means actuated by the holders as they are successively moved from said initial position to move said forming device therewith to clamping position, and means to return said forming 30 device to initial position.
11. In a heel-assembling machine, a series 35 of heel holders successively movable from an initial position, a lift-clamping means for each holder movable into clamping position when the holder is moved from initial position, a heel-forming device and means 40 to hold the same in coöperative relation with each holder when in said initial position, to form the heel thereon, means to connect said 45 forming device to each holder to cause said device to be moved therewith to clamping position, and means to disconnect said device therefrom and to return it to initial position.
12. In a heel-assembling machine, a series 50 of heel holders successively movable from an initial position, a lift-clamping means for each holder movable into clamping position when the holder is moved from initial position, a heel-forming device and means 55 to hold the same in coöperative relation with each holder when in said initial position, to form the heel thereon, and engaging means to connect said forming device to each holder 60 to move the forming device as the holder is moved from initial position, said engaging means being movable to disconnect said forming device and the holder to permit the return thereof to initial position.
13. In a heel-assembling machine, a series 65 of heel-holders, successively movable from an initial position, a lift-clamping means for each holder movable into clamping position as the holder is moved from initial position, a heel-forming device adapted to be 70 held in operative relation with each holder when in initial position, means to move said heel-forming device with each holder to clamping position, a locking device arranged normally to hold said forming device in forming relation, and means to move said locking device to unlocked position and to permit said forming device to be disengaged from the heel when it is moved to clamping position, and means to return said forming 75 device to initial position.
14. In a heel-assembling machine, a series 80 of heel holders and means to move the same successively from an initial position, a heel breast-gage on each holder, heel-forming means adapted to conform to the rear portion of the heel, and means to hold the same in operative relation with each breast-gage when its holder is in initial position, a heel 85 clamping means for each holder, and means permitting movement of said forming means out of operative relation with each heel when clamped on a holder by said clamping means.
15. In a heel-assembling machine, a series 90 of heel holders and means to move the same successively from an initial position, a heel breast-gage on each holder, a pair of fingers having faces adapted to conform to the rear portion of a heel at opposite sides of the 95 middle line thereof, and means to hold the same in operative relation to the breast-gage of each holder when in initial position, means to clamp the heel on each holder while held in position thereon by said fingers 100 and gage, and means permitting movement of one of said fingers to permit the heel, while thus held, to be disengaged therefrom.
16. In a heel-assembling machine, a series 105 of heel-holders successively movable from an initial position, a support adjacent said position, a heel-forming member mounted on each holder to engage one edge portion of the lifts placed thereon, a coöperating heel-forming member mounted on said support 110 in position successively to engage the opposite edge portion of the lifts on said holders when in said position, whereby the lifts may be assembled between said forming members upon each holder, successively, and 115 a clamping device for pressing the lifts on each holder while thus held.
17. In a heel-assembling machine, a series 120 of heel-holders successively movable from an initial position, a support adjacent said position, a heel-forming member mounted on each holder to engage one edge portion of the lifts placed thereon, a coöperating heel-forming member mounted on said support 125 in position successively to engage the opposite edge portion of the lifts on said holders when in said position, whereby the lifts may be assembled between said forming members upon each holder successively, 130 a clamping device for pressing the lifts to-

- gether while held between said members, and means to permit disengaging movement of the member on said support from the lifts after they have been clamped.
5. 18. In a heel-assembling machine, a series of heel-holders successively movable from an initial position and each having a heel-lift-receiving seat, a support, a heel-forming member mounted on said support and movable thereon transversely of the path of said holders 25 to and from a position to hold a series of heel-lifts in heel form on the seat of each holder successively, when the holder is in said initial position, and a clamping device for each holder for pressing the lifts against 30 the seat thereof while held in heel form by said heel-forming member.
10. 19. In a heel-assembling machine, a series of heel-holders successively movable in a 15 while held in heel form by said heel-forming member, the latter being movable out of engagement with the lifts after they have been clamped.
15. 20. In a heel-assembling machine, a series of heel-holders successively movable in a

predetermined path to and from an initial position, and each having a heel-lift-receiving seat, a support, a heel-forming member mounted on said support and movable thereon transversely of the path of said holders 25 to and from a position to hold a series of heel-lifts in heel form on the seat of each holder successively, when the holder is in said initial position, and a clamping device for each holder for pressing the lifts against 30 the seat thereof while held in heel form by said heel-forming member.

In testimony whereof, I have signed my name to this specification, in the presence of two subscribing witnesses.
